CONVEYER

Vincent A. Rayburn and Duer C. Robson, Baltimore, Md., assignors to Western Electric Company, Incorporated, New York, N. Y., a corporation of New York

Application December 21, 1945, Serial No. 636,402

5 Claims. (Cl. 214—89)

1

This invention relates to conveyers and more particularly to conveyers for carrying reels.

In the operation of a conveyer for carrying reels of wire over a closed path, reels being loaded onto such a conveyer must be placed on portions of the conveyer which are not already occupied with reels in order to avoid fouling between reels already on the conveyer and reels being loaded thereon. If reels are loaded manually upon the conveyer, careful and heavy work is required.

An object of the invention is to provide new and improved conveyers.

A conveyer forming one embodiment of the invention comprises an article-engaging element, means for advancing the article-engaging element along a predetermined path, and means for positioning an article in said path. Also provided are pneumatic means including a supply line of compressed air for driving the article positioning means, a valve positioned in the supply line which, when closed, prevents the operation of the article positioning means, a solenoid which, when actuated, closes the valve, means operable by an article carried by the article-engaging element for actuating the solenoid, a second solenoid which, when actuated, opens the valve, and means for actuating the second solenoid.

A complete understanding of the invention may be obtained from the following detailed description of a conveyer constituting a specific embodiment thereof, when read in conjunction with the appended drawings, in which

Fig. 1 is a fragmentary, front elevation of a conveyer forming one embodiment of the invention, with portions thereof broken away, and

Fig. 2 is a fragmentary, diagrammatic view of the conveyer.

Referring now in detail to the drawings, an endless conveyer chain 10 (Fig. 1) serves to carry a plurality of hook assemblies, of which a hook assembly 11 is shown, along an endless track 12. A trolley 15 supports the chain and the hook assemblies on the track, and the chain 10 carries trip rolls, illustrated by a trip roll 16, a predetermined distance in advance of the hook assemblies. The chain is advanced continuously along the track 12 by a suitable sprocket (not shown) and carries the hook assemblies and the trip rolls along the track toward the right, as viewed in Figs. 1 and 2. Since the operation and function of each of the hook assemblies and the trip rolls is the same, only the hook assembly 11 and the trip roll 16 will be referred to in detail.

As the chain 10 advances the hook assembly 11 along the track 12, the trip roll 16 engages

2

an L-shaped cam 17 rigidly secured to a shaft 20 and turns the cam 17 in a counterclockwise direction, as viewed in Fig. 2, from its full-line position to its broken-line position. When the cam 17 is so turned, the shaft 20 also is turned and the shaft turns a vane 21 of a valve 22 from its full-line position to its broken-line position. When the vane is in its broken-line position, the valve 22 connects a supply pipe 25 with a pipe 26, and when air under pressure is supplied to the pipe 25, the air flows through the pipe 26 to the lower portion of a cylinder 27 of an air hoist 28. The air under pressure then forces a piston 30 upwardly in the cylinder 27, and a carriage 31 mounted on a piston rod 32 is raised from its full-line position to its broken-line position. A reel 33 may be positioned on the carriage between stops 34 and 35 secured to the carriage, and when the carriage is raised the reel positioned on the carriage is carried into the path of the hook assembly 11. As the piston 30 is moved upwardly in the cylinder 27, air forced from the upper portion of the cylinder is conveyed by a pipe 40 to the valve 22, which connects the pipe to an exhaust pipe 41. As the hook assembly 11 advances further toward the right a horn 43 enters a hole 44 formed in the reel 33. Meanwhile, the trip roll 16 rolls along a dwell portion 45 formed on the cam 17 and maintains the cam in its broken-line position so that the vane 21 is kept in a position in which the pipe 25 is connected with the pipe 26. When the horn 43 is directly over the carriage 31, the horn 43 will be substantially full-way into the hole 44 of the reel 33. At that point the trip roll 16, which has passed beyond the cam 17, engages an L-shaped cam 46 and moves the cam 46 from its broken-line position to its full-line position, whereby a link 47 connected to a projection 48 of the cam 17 is moved in a clockwise direction from its broken-line position to its full-line position. When the arm 48 is so moved, the vane 21 is moved from its broken-line position to its full-line position so that the supply pipe 25 is connected with the pipe 40 and the exhaust pipe 41 is connected with the pipe 26. Air under pressure is supplied through the pipes 25 and 40 to the upper portion of the cylinder 27 and forces the piston 30 to the bottom of the cylinder. Meanwhile, the pipe 26 serves to exhaust the lower portion of the cylinder 27 and guides air contained therein to the exhaust pipe 41. As air is supplied to the upper portion of the cylinder 27 and the air in the lower portion of the cylinder 27 is exhausted, the carriage 31 is moved downwardly away from the reel 33 leaving the reel deposited

upon the horn 43, which carries the reel along the track 12.

While the carriage 31 is being lowered the trip roll 16 rolls along a dwell portion 49 of the cam 46. After the trip roll 16 has moved from the dwell portion 49 of the cam 46, it strikes an arm 50 connected to a contactor 51 of a normally open reset switch 52 and moves the contactor into engagement with a contact 53 of the reset switch. The contact 53 is connected by a conductor 55 to a conductor 56 of a power line 57. The contactor 51 is connected by a conductor 60 to a winding 61 of a solenoid 62, and the winding 61 is connected by a conductor 66 to a conductor 67 of the power line 57.

When the contactor 51 is moved into engagement with the contact 53, the winding 61 of the solenoid 62 is energized, whereby an armature 68 of the solenoid 62 is raised and raises a valve head 70 having tapered ends 71 and 72. The solenoid 62 and the valve head 70 form a portion of a valve assembly 75, and the valve head 70 is mounted in an auxiliary valve chamber 76 of the valve assembly and normally is pressed against a valve seat 77 by a compression spring 78. When the solenoid 62 is actuated it raises the valve head 70 out of engagement with the valve seat 77 and into engagement with a valve seat 79 formed in the opposite end of the auxiliary valve chamber 76, whereby an exhaust port 80 is opened and a supply port 81 is closed. The supply port 81, when open, connects the chamber 76 to a supply passage 82 in the valve assembly 75 connected to a main supply pipe 85 leading from a supply of air under pressure (not shown).

When the exhaust port 80 is opened to the auxiliary valve chamber 76, it serves to exhaust air from the valve chamber 76 and from the end of a main valve chamber 86 connected with the auxiliary valve chamber 76 by a connecting port 87. The valve chamber 86 is connected to the supply pipe 85 by an inlet port 90 and is connected to the supply pipe 25 by an outlet port 91. A connecting port 92 serves to connect the main valve chamber 86 to an auxiliary valve chamber 95 in which a valve head 96 having tapered ends 97 and 98 is mounted. The tapered end 97 is designed to fit against a valve seat 100 and the tapered end 98 is designed to fit against a valve seat 101. The valve seat 100 terminates a supply port 103 connected with a supply passage 104 leading to the supply pipe 85 and the valve seat 101 terminates an exhaust port 105. The valve head 96 is urged downwardly, as viewed in Fig. 2, by a compression spring 106, which normally holds the tapered end 98 of the valve head 96 against the valve seat 101 to close off the exhaust port 105.

When the solenoid 62 is actuated, the tapered end 71 of the valve head 70 is moved into engagement with the valve seat 79, whereby the valve chamber 76 is closed from the supply passage 82 and the main supply pipe 85. The exhaust port 80 then exhausts any air under pressure in the valve chamber 76, so that the air under pressure in the left end of the main valve chamber 86, as viewed in Fig. 2, presses against the left hand end 110, as viewed in Fig. 2, of a piston 111, which is connected by a rod 112 to a piston 115. The pistons 111 and 115 and the rod 112 are mounted for free sliding movement in the main valve chamber 86 and are moved to the right by the air under pressure until the right hand end 116 of the piston 115 engages the right end of the valve chamber.

When the pistons 111 and 115 and the rod 112

are so moved, the piston 115 moves from its broken-line position, as seen in Fig. 2, to its full-line position. When the piston 115 is in its broken-line position, it closes off the inlet port 90 from the outlet port 91, but when the piston 115 is in its full-line position, the air is free to pass from the inlet port 90 to the outlet port 91. Thus, when the piston 115 is in its full-line position, air under pressure from the main supply pipe 85 is supplied to the supply pipe 25 and is conveyed by the latter to the valve 22. Thus, when the L-shaped cam 17 is moved from its full-line position to its broken-line position, compressed air is supplied to the pipe 26 to raise the hoist 28.

An armature 119 of a solenoid 120 is connected to the valve head 96 and is raised when a winding 121 of the solenoid 120 is energized. When the winding 121 is energized, the tapered end 97 of the valve head 96 is moved into engagement with the valve seat 100, and the valve chamber 95 is shut off from the passage 104 and is connected with the exhaust port 105. When the valve chamber 95 is shut off from the passage 104 and the exhaust port 105 is connected with the valve chamber 95, air is exhausted from the left end of the main valve chamber 86. This creates an unbalance of pressure on the ends of the pistons, and air under a greater pressure pressing against the end 116 of the piston 115 urges the pistons 115 and 111 and the rod 112 toward the left to their broken-line positions, in which positions the end 116 of the piston 111 strikes the left end of the valve chamber 86. At this time, the piston 115 serves to shut off the inlet port 90 from the outlet port 91, and when the vane 21 is moved from its full-line position to its broken-line position, no air under pressure is supplied to the lower portion of the cylinder 27 and the carriage 31 is not raised.

The winding 121 is connected to the conductor 67 of the power line 57 by a conductor 125 and the conductor 66, and a conductor 126 serves to connect the winding 121 to a contactor 127 of a block-out switch 130, which includes a contact 131. The contact 131 is connected by a conductor 132 to the conductor 56 or the power line 57. When the hook assembly 11 approaching the loader carries a reel, illustrated by a reel 135, toward the hoist 28, the reel 135 strikes a shoe 136 and moves the shoe from its full-line position, as seen in Fig. 2, to its broken-line position. The shoe 136 is connected to an arm 137 and a counterweighted arm 138, and, when the shoe 136 is engaged by the reel 135, the shoe, the arm 137 and the counterweighted arm 138 are moved from their full-line positions to their broken-line positions and the arm 137 closes the switch 130. When the switch 130 is closed, the winding 121 of the solenoid 120 is energized, thereby causing the valve assembly 75 to shut off the supply pipe 85 from the supply pipe 25, so that no compressed air is supplied to the valve 22 until the solenoid 62 is again actuated.

The hook assembly 11 moves the reel 135 out of engagement with the shoe 136 and the trip roll 16 strikes the L-shaped cam 17 and moves it from its full-line position to its broken-line position. This turns the L-shaped cam 46 and the vane 21 from their full-line positions to their broken-line positions. While the supply pipe 25 and the pipe 26 are connected at this time, no air under pressure is supplied to the supply pipe 25 and the hoist 28 is not raised so that no reel 135 carried on the hook assembly 11.

The hook assembly 11 then carries the reel 135 above the hoist 28, the trip roll 16 engages the L-shaped cam 46 and moves it from its broken-line position to its full-line position, and the vane 21 is moved from its broken-line position to its full-line position. The trip roll 16 then strikes the arm 50 and the contactor 51 is moved into engagement with the contact 53, and the winding 61 of the solenoid 62 is energized. The solenoid 62 draws the valve head 70 upwardly and moves the tapered end 71 thereof into engagement with the valve seat 79, and the tapered end 72 thereof out of engagement with the valve seat 77. This exhausts air from the auxiliary valve chamber 76, and air under pressure at the left end of the main valve chamber 86 urges the pistons 111 and 115 from their broken-line positions to their full-line positions thereby connecting the supply pipe 85 to the supply pipe 25.

After the pistons 111 and 115 have been so moved, the trip roll 16 moves out of engagement with the arm 50 and the engagement between the contactor 51 and the contact 53 is broken, which deenergizes the winding 61. The valve head 70 then is urged by the compression spring 78 against the valve seat 77 and away from the valve seat 79, whereby the supply port 81 is opened to the auxiliary valve chamber 76. Air under pressure then is supplied to the chamber 76 and the connecting port 87, but the air under pressure in the left end of the main valve chamber 86 keeps the slideable pistons 111 and 115 in their full-line positions. When a hook assembly (not shown) similar to the hook assembly 11, but not carrying a reel, is advanced by the chain 10 toward the hoist 28, and a trip roll (not shown) identical with the trip roll 16 carried by the chain 10 engages the L-shaped cam 17 and moves it from its full-line position to its broken-line position, air under pressure is supplied to the lower portion of the cylinder 27 and the hoist 28 is actuated. The hoist 28 then moves upwardly and carries a reel thereon into the path of the hook assembly, which advances to a position in which the horn enters the hole in the center of the reel. When the hook assembly is directly over the hoist 28, the trip roll strikes the cam 46 and moves it from its broken-line position to its full-line position. This actuates the valve 22 to guide air under pressure to the upper portion of the cylinder 27 and exhaust air from the lower portion of the cylinder. This causes the carriage 31 to be lowered from its broken-line position to its full-line position leaving the reel on the horn.

In the operation of the conveyer described hereinabove, the chain 10 (Fig. 1) carries the hook assembly 11 along an endless path formed by the track 12 and carries the trip roll 16 at a predetermined distance in advance of the hook assembly 11. If the horn 43 of the hook assembly 11 is not loaded and is advanced toward the hoist 28, the trip roll 16 engages the L-shaped cam 17 to actuate the valve 22, to connect the supply pipe 25 to the pipe 26 and air under pressure actuates the hoist 28, whereby the piston 30, the piston rod 32 and the carriage 31 are raised from their full-line positions to their broken-line positions and the reel 33 is positioned in the path of the hook assembly 11. The hook assembly 11 continues to advance to a position directly over the carriage 31, in which position the horn 43 enters the hole 44 in the reel 33. At this time, the trip roll 16 moves out of engagement with the dwell portion 45 of the cam 17 and into engagement with the L-shaped cam 46, which has been

moved to its broken-line position, and moves the L-shaped cam 46 from its broken-line position to its full-line position, whereby the valve 22 is actuated to the lower the hoist and the reel 33 is lowered upon the horn, which retains the reel thereon. Meanwhile, the hook assembly 11 and the trip roll 16 continue their movement toward the right, as viewed in Fig. 2, and the trip roll 16 moves into engagement with the arm 50 and 10 closes the switch 52, whereby the solenoid 62 is actuated and air is exhausted from the auxiliary valve chamber 76 so that the pistons 111 and 115 and the rod 112 are maintained in their full-line positions and the valve 22 is operatively connected with the supply pipe 85.

The trip roll 16 moves out of engagement with the arm 50 and the reel 33 is carried along the endless path. The reel 33 then is removed from the hook assembly 11 at a point on the endless 20 path where it is needed and the hook assembly is advanced back toward the loader where the above-described operation is repeated with another reel similar to the reel 33.

When the hook assembly 11 carries a reel 135 thereon, which has been previously loaded thereon by the loader but has not been unloaded prior to the approach of the hook assembly 11 toward the loader, it is essential that a reel placed on the hoist 28 is not raised into a position similar 30 to the broken-line position of the reel 33 in order that fouling be avoided. As the hook assembly 11 and the reel 135 are advanced toward the loader 28, and before the trip roll 16 strikes the L-shaped cam 17, the reel 135 engages the shoe 136 and 35 moves it from its full-line position to its broken-line position, whereby the switch 130 is closed. The closing of the switch 130 causes the pistons 111 and 115 and the piston rod 112 to be moved to their broken-line positions and the valve 22 40 is closed off from the supply of compressed air. The trip roll 16 then moves into engagement with the L-shaped cam 17 and moves it from its full-line position to its broken-line position. But the hoist 28 is not raised because air under pressure is cut off from the valve 22 at this time.

The reel 135 is moved out of engagement with the shoe 136, which is moved back from its broken-line position to its full-line position by the counterweighted arm 138, whereby the switch 130 is 50 opened. When the switch 130 is opened, the winding 121 of the solenoid 120 is deenergized, whereby the valve head 96 is urged by the compression spring 105 to the position in which it is shown in Fig. 2. However, such movement of the 55 valve head 96 does not cause any change of position of pistons 111 and 115 because the air under pressure pressing against the end 116 of the piston 115 maintains the pistons 111 and 115 in their broken-line positions. The hook assembly 11, 60 the reel 135 and the trip roll 16 continue to advance to the right and the trip roll engages and moves the L-shaped cam 46 from its broken-line position to its full-line position, whereby the valve 22 is actuated to close off the supply pipe 25 from 65 the pipe 26. The trip roll then moves into engagement with the arm 50 and closes the switch 53, whereby the solenoid 62 is actuated and the pistons 111 and 115 and the rod 112 are moved from their broken-line positions to their full-line 70 positions so that the valve 22 is operatively connected with the supply pipe 85. Thus the hoist 28 can be actuated by a trip roll associated with an unloaded reel assembly.

The loader serves to load reels surely and effectively on the hook assembly 11 and the other hook

assemblies are carried by the chain 10 at spaced points therealong, and prevents fouling between reels carried by the hook assemblies and reels placed upon the hoist 28 as the hook assemblies are carried over the hoist.

What is claimed is:

1. In a conveyor, an article-engaging element, means for advancing the article-engaging element along a predetermined path, pressure-actuated means for positioning an article in said path, a valve for preventing the operation of the pressure-actuated means when in one position and for permitting the operation thereof when in a second position, a solenoid for moving the valve to the first position when actuated, a second solenoid for moving the valve to the second position when actuated, means placed adjacent to said path in a position in which it is engaged by an article carried by the article-engaging element when the article-engaging element carries the article toward the article-positioning means for actuating the first-mentioned solenoid, whereby the valve is moved to the first position, and means associated with the article-engaging element for actuating the second solenoid after the article-engaging element has been advanced beyond the article-positioning means.

2. In a conveyor, means for conveying articles along a predetermined path, means for placing an article on the article-conveying means, a supply line for supplying air under pressure to the article-placing means to drive the placing means, a valve positioned in the supply line for closing the supply line to prevent the driving of the article-placing means, a solenoid for closing the valve when actuated, a second solenoid for opening the valve when actuated, means positioned adjacent to said path for actuating the first solenoid when a full portion of the article-conveying means approaches the article-placing means, and means positioned adjacent to said path for actuating the second solenoid when a full portion of the article-conveying means leaves the article-placing means.

3. In a conveyor, a loader, means for conveying articles past the loader, pressure-actuated means for actuating the loader to load articles on the article-conveying means, a supply line for supplying a fluid under pressure to the pressure-actuated means, a valve positioned in the supply line for preventing the actuation of the loader when closed, a solenoid for closing the valve when actuated, a second solenoid for opening the valve when actuated, a switch for actuating the first solenoid when closed, means positioned in the path of an article carried by a portion of the article-conveying means approaching the loader for closing the switch, a second switch for actuating the second solenoid when closed, and means carried by the conveying means for closing the second switch after a loaded portion of the article-conveying means is advanced past the loader.

4. In a conveyor, a loader, a hook assembly, means for advancing the hook assembly past the loader, pressure-actuated means for driving the loader, a supply line for supplying a fluid under pressure to the pressure-actuated means, a valve positioned in the supply line for preventing the operation of the loader when closed, a solenoid for closing the valve when actuated, a switch for actuating the solenoid when closed, means positioned adjacent to the path of an article carried by the hook assembly as the article and the hook assembly are advanced toward the loader for closing the switch, a second solenoid for opening the valve when actuated, a second switch for actuating the second solenoid, and means carried by the hook assembly advancing means for closing the second switch after the hook assembly has been advanced past the loader.

5. In a conveyor, a hook assembly, a hoist for raising reels, means for advancing the hook assembly over the hoist, pneumatic means for raising the hoist, a supply line for supplying air under pressure to the pneumatic means, a valve positioned in the supply line, means for opening the valve, a striker carried by the hook assembly, advancing means for actuating the valve-opening means when the hook assembly is advanced toward the hoist, whereby the hoist raises a reel into the path of the hook assembly, means for closing the valve to cause the hoist to be lowered, said means being carried by the advancing means and serving to actuate the valve-closing means when the hook assembly is advanced to a position over the hoist, a second valve positioned in the supply line in series with the first-mentioned valve, a solenoid for closing the second valve when actuated, a switch for actuating the solenoid when closed, means positioned adjacent to the path of the hook assembly for closing the second switch when struck by a reel carried by the hook assembly when the hook assembly is advanced toward the hoist, a second solenoid for opening the second valve when actuated, a second switch for actuating the second solenoid when closed, said second switch being positioned in the path of the striker at a point where the striker strikes the second switch after the hook assembly has been advanced past the hoist.
